UNITED STATES PATENT OFFICE.

LEWIS E. MORRISON, OF NEWARK, NEW JERSEY, ASSIGNOR TO HUMANA COMPANY, A CORPORATION OF NEW JERSEY.

TRIPPING MECHANISM FOR PRINTING-MACHINES.

1,201,329.

Specification of Letters Patent.

Patented Oct. 17, 1916.

Application filed November 20, 1915. Serial No. 62,462.

To all whom it may concern:

Be it known that I, LEWIS E. MORRISON, a citizen of the United States, and a resident of Newark, in the county of Essex and State 5 of New Jersey, have invented certain new and useful Improvements in Tripping Mechanisms for Printing-Machines, of which the following is a specification.

This invention relates to tripping mechanisms 10 for printing machines and has particular reference to a tripping or throw off device adapted for platen job presses, though of course I claim the use of my invention on other machines to which it may be 15 adapted.

The object of the invention is to provide a tripping mechanism of generally improved construction and design and automatic in its operation.

20 Another object of the invention is to construct the tripping device in such a manner that it may be attached to the press or machine without requiring any material alteration in the construction thereof.

25 In the following specification and as illustrated in the accompanying drawing I have shown my invention applied to a printing machine having a suction operated sheet separating and feeding mechanism, the suction 30 being obtained by means of a suitable pump. The tripping mechanism is also arranged to operate by means of suction created in certain parts thereof from the same pump. However, it will appear and should 35 be understood, that the pump which is an element in the tripping mechanism need not also be an element in any of the mechanisms constituting the machine to which the tripping device is attached, but that in 40 the present instance the suction separating mechanism of the press is simply a timing element in the tripping device. Any other element may be found useful to actuate the suction pump in the tripping mechanism at 45 the proper time to cause the trip to operate.

In accordance with the several objects of my invention as stated above or as will hereinafter appear, my tripping mechanism comprises such parts, elements and combinations thereof as are described in the following specification and as illustrated in the accompanying drawing in which—

50 Figure 1 is a side elevation of a machine equipped with my improved tripping mechanism. The machine is shown as being of

a well known type of job press illustrated sufficiently to understand the operations of the invention. Fig. 2 is an enlarged view of the tripping means, and Fig. 3 is a detail sectional view of the suction mechanism 60 in the tripping device.

Referring to Fig. 1 the numeral 5 denotes the frame of the press; 6 is the platen which oscillates in the usual manner on its pivot 7. The form member 8 is pivoted at 9 and is operated by the connecting rods 10, one on each side of the machine and pivoted to the gear 11 on the one side of the machine and to the platen locking cam 12 on the other side, the gear 11 and cam 12 being 70 mounted on a shaft 13 driven in any suitable manner. All of the aforesaid parts and their operations are well understood in the art.

75 14 is a feed board supporting the sheets 15 from which the top sheet is separated and fed to the platen by a suction separating device 16 carried by an arm 17 pivoted to a lever 18 which is oscillated on its pivot 19 by means of the cam roll 20 and cam 21, 80 the latter being carried on a shaft 22 having a gear 23 which meshes with the gear 11 aforesaid. The shafts 19 and 22 are journaled in an auxiliary frame 24 which also supports the suction pump 25 pivoted at 26 and connected by flexible tubing 27 to the suction device 16 as shown. The shaft 22 85 also operates the pump 25 by means of a crank 28 adjustably secured to the pump piston stem 29 by means as at 30. The rotation of the shaft 22 operates the piston in the pump to create suction in the device 16 which thereupon sucks up the top sheet from pile 15 and as the cam 21 rotates, the lever 18 and arm 17 are moved to the right or rear in 90 Fig. 1 and the separated sheet is fed to and deposited upon the platen as shown in dotted lines, the stroke of the pump being adjusted at 30 to release the suction at any predetermined time whereby to permit the sheet 100 to be placed on the platen in any predetermined position. The operation of these parts is described and illustrated in detail in my pending application Serial Number 59161, filed November 2nd, 1915, and 105 the above description is sufficient for the purpose of understanding the operation of the tripping mechanism.

110 The numeral 31 denotes the tripping lever which is pivoted at 32 and connected at 33

to a link 34 which is pivoted at 35 to an arm 36 fast on a rock-shaft 37. Between the frames of the press the shaft 37 carries an arm 38 to which is fixed a pin 39. This pin travels in a slot 40 in the bell crank 41 on a shaft 42. A link 43 connects the bell crank with an arm 44 on the shaft 45 which carries the form in the form member 8. The shaft 45 is mounted eccentrically in the form member as usual.

On a job press of the type illustrated and not equipped with an automatic trip, the aforesaid elements, which are parts of the press, are operated by the attendant who 15 throws the tripping lever 31 which operates the said arms 36 and 38, the bell crank 41 and the link 43 to lift the arm 44 to turn the shaft 45 in its eccentric bushings to move the form a slight distance away from the 20 platen during the closing of the press on the printing stroke. With the trip provided by this invention, the tripping takes place automatically. For this purpose the tripping lever 31 is connected to the form member 25 in such a manner that when the press closes the tripping lever will be thrown to tripping position as illustrated in Fig. 1. On the trip lever 31 is pivoted at 91 a bracket 48 having two loops 49, 49 through which a 30 slide bar 46 pivoted at 47 to the one connecting rod 10 is adapted to slide. The bar 46 carries a button 90 adapted to engage the bracket to move the trip lever to the right on the opening of the press and after it has 35 been tripped. On the bracket 48 there is pivoted at 50 a latch dog 51 adapted to engage a recess 52 on the bar 46 so that when the latter moves to the left it will throw the trip lever to the left to trip the press. 40 Below the latch dog is pivoted at 53 a latch 54 having a button 55 adapted to engage one of the two sockets 56 and 57 of the spring 58.

59 is a spring secured to the latch 51. The 45 latch 54 is further provided with a stop 60 upon which rests a finger 61 pivoted at 53. 62 is a trip rod or pull pivoted to the finger at 63, and 65 is a trip resetting hook on the bar 46.

50 The principle of operation of the trip actuating mechanism carried on the trip lever 31 is that normally this mechanism is operated into inactive position during the opening stroke, but is reset during the closing stroke. If, however, a sheet misses, the 55 actuating mechanism is not operated on the opening stroke but remains active to cause tripping on the closing stroke. And if several sheets miss in succession, the trip lever 60 31 is operated constantly to trip during each closing stroke of the form. During the normal operation of the press the trip lever remains stationary in a position inclined to the right and opposite to that 65 shown in Fig. 1 and the bar 46 slides idle

in the loops 49. On the opening stroke of the press the trip rod 62 is operated, as will hereinafter appear, to pull down the finger 61 and latch 54, the latter locking itself at 57. The downward movement of the latch 54 permits the latch dog 51 to move down by gravity and the connection between the bar 46 and the trip lever is broken so that on the succeeding leftward or closing stroke of the press, the recess 52 will pass over the latch dog 51 without engaging the same. When the closing stroke is nearly finished, the resetting hook will engage the latch 54, lifting the latter up and put tension on the spring 59. Again on the opening stroke the trip rod 62 will be operated and the latch will again be moved down and the latch dog will remain down and will not engage the recess 52. In other words, during the normal operation of the press the trip actuating mechanism is constantly operated by the rod 62 into inactive position, but reset on the closing stroke. If, however, a sheet misses, then the rod 62 is not operated on the opening stroke. The actuating mechanism remains active, that is the latch dog 51 remains up and on the closing stroke the recess 52 catches hold of said latch dog and carries the trip lever over to the left to trip the press as shown. On the succeeding opening stroke the trip lever is moved back to the right by the button 90 and remains there unless a sheet again misses.

In detail the tripping takes place as follows: When a sheet misses, the latch dog 51 remains up; therefore when the slide bar 46 moves to the right on the opening stroke, the recess 52 will pass over said dog which will snap up into said recess by the spring 59 and consequently on the closing stroke the trip lever will be moved to the left thereby operating the trip. On the succeeding opening stroke the trip lever will be taken back with the bar 46 because the button 90 will engage the adjacent loop 49. During this last named opening stroke the latch dog will remain up if a sheet again misses and the press will be tripped for the second time and so on. But if the sheet does not miss, the latch will be pulled down, and the actuating mechanism will again remain inactive, though being reset on the closing stroke, and the press will not be tripped.

The means for pulling down the trip rod 62 at the proper time are as follows: 67 is a vacuum or suction trip cylinder which is movably carried on the piston 68. The latter is secured to the hollow piston rod 69 which is fixed to the trip lever 31 at 70 in any suitable manner. The piston rod is connected by the hose 71 to the pump 25 so that the suction stroke of the pump creates a vacuum in the cylinder 67 above the piston 68 whereby the cylinder will be pressed down upon the piston by the pressure of the 125 130

atmosphere and as the cylinder moves down the trip rod 62 will also move down as it is secured to the cylinder at 81. 73 is a spring interposed between a fixed collar 74 on the piston rod and a partition 75 on the cylinder to normally raise the latter. To the press is secured a fixed cam 76 having a spring arm 77 with a button 78. Rotatably mounted upon the pivot 79, which connects 10 the connecting rod 10 to the platen locking cam 12, is a cam 80, which rotates with said locking cam 12 and at the same time rotates on its pivot 79. Therefore, when the press is about to open, the cam 80 moves down- 15 ward and into the path of the button 78, moving it and the cam 76 away from the trip cylinder 67, or to the right in Fig. 3, so that if the suction device 16 is picking up a sheet, vacuum will be created in the cylinder 67 and the latter will move down, taking trip 62 with it and the press will not be tripped. When the suction device 16 does not pick up a sheet, the suction stroke of the pump will not create a vacuum in the 20 trip cylinder and the latter will not move down, even though the cam 76 has been moved away therefrom. The trip cylinder is provided with a shoulder 83 which is immediately above the cam 76 so that this cylinder cannot move down unless the cam 76 is pulled away therefrom. Thus the removal of the cam 76 permits the trip cylinder to act as soon as the latter, moving with the trip lever 31, has cleared the 25 cam 76 thereby giving the suction device 16 time to act if the sheet is picked up. If the cam 76 was not provided, the trip cylinder would act as soon as the pump commenced its suction stroke which would be 30 too soon for the various elements to operate and the press would be untripped prematurely. Thus it will be seen that during the regular operation of the press, it is constantly untripped because the obstruction, 35 the cam 76, is removed from the trip cylinder permitting the latter to move down to untrip, while if there is no sheet picked up the trip cylinder will not move down because of no vacuum and the press will remain 40 tripped. The cam 76 is preferably toothed as shown to facilitate the downward movement of the cylinder 67 in that the shoulder 83 will slide off of a point of a tooth more easily than if the upper surface of the cam 45 were plain.

The construction of the finger 61 resting upon the stop 60 permits of a certain amount of play in the operation of the parts which occurs because of the swinging of the several 50 parts of the tripping mechanism around different centers.

From the foregoing it is apparent that the suction feeding device is the controlling element which sets the actuating mechanism 55 on the trip lever to avoid tripping and

leaves the actuating mechanism inactive to cause tripping by the operation of the trip lever. When the device operates properly, meaning that it picks up a sheet, the admission of air to the trip cylinder 67 is prevented and a vacuum is created within said cylinder and the trip does not operate. 70

It is obvious that I may use other elements of the machine to vary the air pressure in the trip cylinder, the main feature being, 75 that the absence or presence of atmospheric pressure within the said cylinder causes it to operate or remain inactive for the purposes of operating the trip. Other details of the construction herein set forth may also be 80 changed without departing from the spirit of the invention and the scope of the appended claims.

I claim:

1. In a printing machine, the combination 85 of a movable form member, a tripping mechanism for the same, a movable member for connecting said tripping mechanism and the said form member to trip the press during the impression stroke and means on said 90 movable member responsive to atmospheric pressure for rendering said movable member inoperative to prevent tripping.

2. In a printing mechanism the combination 95 of a movable form member, a tripping mechanism, a movable element for connecting said tripping mechanism and the said form member to trip the press, a cylinder connected to said movable element and means for varying the air pressure within 100 said cylinder to cause the same to operate in response to atmospheric pressure to render the said movable element inactive to prevent tripping.

3. The combination of a movable form 105 member, a tripping mechanism therefor, a lever for operating the latter, devices for connecting said form member and said lever during the impression stroke to trip the press, a suction-operated sheet feeding mechanism and suction means for actuating the latter and for operating the said connecting devices into inoperative position when a sheet is fed by said sheet feeding mechanism, and means for resetting said connecting device into operative position. 110

4. The combination of a movable form element, a tripping mechanism therefor, a member for operating said tripping mechanism, devices on said member for causing 120 the operation of the same, suction operated means for positioning said devices to render the said member inoperative and means for resetting the said devices to cause tripping.

5. The combination of a movable form 125 member, a tripping mechanism therefor, a normally stationary member for operating said tripping mechanism, devices for causing the operation of said stationary member, a suction operated element for positioning 130

said devices to operate said stationary member to trip the form member and means operated from the latter for re-positioning said devices to prevent operation of said stationary member.

6. The combination of a form member, a tripping mechanism therefor, a lever for operating said tripping mechanism, coöperating devices on the said lever and the said 10 form member, the coöperation of said devices tending to trip said form member and a member operable in response to atmospheric pressure for preventing the coöperation of said devices and means for causing the operation of said last named member.

7. The combination of a form member, a tripping mechanism therefor, a lever for operating said mechanism, a latch mechanism, a movable element adapted to coöperate with 20 said latch mechanism to actuate the said lever once during each operation of the said form member, a movable cylinder, means for varying the air pressure within said cyl-

inder to cause the same to move and mechanism operated by said cylinder for positioning the said latch mechanism to prevent it from coöperating with the said movable element.

8. The combination of a form member, a tripping mechanism therefor, a lever for operating said mechanism, a latch mechanism, a movable element adapted to coöperate with said latch mechanism to actuate the said lever once during each operation of the said form member, a movable cylinder, means for varying the air pressure within said cylinder to cause the same to move, mechanism operated by said cylinder for positioning the said latch mechanism to prevent it from coöperating with the said movable element, and means on the latter for resetting said latch mechanism into coöperative position.

Signed at Newark in the county of Essex and State of New Jersey this 16th day of November, A. D. 1915.

LEWIS E. MORRISON.
